UNITED STATES PATENT OFFICE.

ROBERT EMIL HENRIKSEN AND ANDERS JENSEN, OF KORSOR, DENMARK.

TWO-STROKE-CYCLE ENGINE.

Application filed June 19, 1919. Serial No. 393,229.

To all whom it may concern:

Be it known that we, ROBERT EMIL HENRIKSEN and ANDERS JENSEN, subjects of the King of Denmark, both residing at Korsor, Denmark, have invented new and useful Improvements in Two-Stroke-Cycle Engines, of which the following is a specification.

The present invention consists in an arrangement in two-stroke cycle engines of the kind by which there is built into the working piston a fuel pump compressing the fuel for the next piston stroke, while the piston is moving outward. The novel feature of the invention is that the working piston of the engine is shaped as a cylinder with bottom, and encircles a stationary piston supported by fixed feet, wherein the channels conveying the fuel to and from the working chamber of the fuel pump are located.

A further novel feature of the present invention is that the walls of the working piston of the engine are of such thickness that the effective volume swept by the piston of the fuel pump is equal to or nearly equal to the cylinder volume swept by the engine piston, when deduction is made for the portion of the length of piston stroke, during which the exhaust channel is open.

Two different manners of constructing the invention are shown on the drawing, where

Fig. 1 shows a single-cylinder two-stroke cycle engine, in vertical section,

Fig. 2 a section along the line II-II in Fig. 1,

Fig. 3 a vertical section of a modified construction of the engine working piston and the parts belonging thereto, and

Fig. 4 the same in side elevation.

From the suction-valve 3 of the engine, a channel 4 extends to the injection-valve 5 of the engine cylinder. The working chamber of the engine cylinder is marked 6, and the working piston of the same is marked 7. This piston is packed against the engine cylinder wall, in known manner, by means of piston rings 8. In the construction shown in Figs. 1 and 2, there is provided, across the piston 7, a pin 9 which is connected, by means of a connecting rod 10, to the engine crank 11. This latter is adapted to revolve within the crank-casing 12 of the engine. The working chamber 6 communicates with one or more exhaust-channels 13.

The piston 7 is hollow and encircles a fixed piston 14 with piston rings 15. The piston 14 is supported by one or more fixed feet 16 in firm connection with a ring or disc 17 inserted between the engine cylinder and the crank-casing 12. In the feet 16, there are provided channels 18 and 19 connecting the space 20 above the piston 14 with an annular channel 21 in the member 17. This channel is connected, by way of a channel 22, with the suction valve 3 and the above mentioned channel 4.

The engine works in the following manner:

When the piston 7 moves upward, and compresses the fuel present in the chamber 6, fresh fuel will be inhaled, by way of the valve 3 and the channels 22, 21, 19 and 18 to the compression chamber 20 of the fuel pump. When the piston 7 has reached its topmost position, the charge present in the chamber 6 will be ignited in known manner, and the combustion of the charge will then drive the piston 7 downward. By this motion, the fuel present in the compression chamber 20 of the fuel pump will be compressed.

When the piston 7 approaches its bottom-most position, it opens the exhaust channel 13, and the combustion gases present in the chamber 6 will then flow out through this channel. Hereby a drop of pressure is caused in the chamber 6, and the fuel compressed in the chamber 20 of the fuel pump and in the channels 18, 19, 21, 22 and 4 will then open the valve 5 and flow into the space 6. The entering fuel will push the combustion gases forward and out through the channel 13, so that a thorough scavenging of the working chamber of the engine cylinder is attained.

When then the piston 7 moves upward again, it will close the exhaust valve 13, the channel 5 will close itself and, by way of the admission valve 3, there will be inhaled fresh fuel, which flows to the chamber 20 of the fuel pump by way of the channels 22, 21, 19 and 18.

By the present invention, there is attained the advantage that the height of the engine is not essentially increased, although the fuel pump is inserted between the engine cylinder and the crank-case. By locating the channels 18 and 19 in the feet 16 of the piston 14, the advantage has been attained that the walls of the piston 7 may be made

quite thin, so that the effective volume swept by the piston of the fuel pump may be made as large as the present construction will permit. The feature that the walls 5 and bottom of the piston 7 are quite thin offers the further advantage that the heat of the combustion gases will be easily and quickly transmitted to the fuel compressed in the fuel pump, so that this fuel is pre-10 heated, simultaneously with the engine piston 7 being cooled by the fuel flowing through the fuel pump.

In the construction shown in Figs. 3 and 4, the stationary fuel-pump piston 14 is 15 not supported by two feet but only by one, viz a tube 23 disposed centrally with respect to the working piston by way of which the fuel is conveyed to and from the working chamber 20 of the fuel pump. The connecting rod connecting the engine working piston 7 to the engine crank is replaced by two rods disposed one on either side of the said tube.

By this arrangement there is attained a 25 particularly cheap construction especially suitable for smaller engines.

The lower end of the tube 23 is screwed into a plate 26, which is fastened to the working cylinder of the motor (not shown 30 in this figure, but the same as in Fig. 1). The cavity of the tube 23 communicates with a tube 27 attached to the lower side of the plate 26. The tube 27 communicates with the admission valve 3 (Fig. 1) of the 35 fuel pump and with a channel (4, Fig. 1) leading to the working chamber of the engine.

Connected to the piston 7 is a plate 28 with two diametrically opposite cylindrical 40 pins 29 and 30 journaled in bearings 31, 32 in the wall of the piston 7. The pitman rods 24 and 25 are screwed to the plate 28, and these rods connect the plate 28 to a ring 33 encircling a crank 34 on the engine 45 shaft 11. In the plate 26, there are provided two slots 35 and 36 affording passage for the rods 24 and 25, so that the latter are free to swing forward and backward following the motion of the crank 34. In 50 similar manner there is provided, in the plate 28, an opening 37 through which the tube 23 is inserted and which is so large that the plate 28 may perform its oscillating motion, without being hampered by the 55 tube 23.

When the engine works, the piston 7 moves up and down relatively to the stationary piston 14, and the fuel inhaled into and expelled from the working chamber 20 60 of the fuel pump passes in and out by way of the tubes 23 and 27.

Having now particularly described and ascertained our said invention and the mat-

ter in which the same is to be performed, we declare that what we claim is:—

1. In a two-stroke internal combustion engine, comprising a working cylinder, a stationary piston located within said working cylinder having external packing, and a hollow working piston reciprocating within the 70 working cylinder and on the packed outer surface of said stationary piston to form a combustion chamber within the working cylinder, and a fuel pump and compression chamber between said pistons, a fuel admission valve and a passage leading thence to said compression chamber, a passage leading from such chamber to the inlet to the combustion chamber, and a valve at said inlet, the piston displacement of said fuel pump chamber approximating that of the working chamber before the opening of the exhaust passage, whereby the fuel is first drawn into such chamber, and during the combustion stroke is compressed therein, and expelled 85 therefrom to the combustion chamber.

2. In a two-stroke internal combustion engine, comprising a working cylinder, a stationary piston concentrically located in said working cylinder, and having external packing, and a hollow working piston reciprocating within the working cylinder and on the outer surface of said stationary piston to form a combustion chamber within the working cylinder, and a compression chamber 95 between said pistons, the working cylinder having an exhaust port uncovered toward the end of the power stroke, a fuel admission valve, a passage communicating therefrom to the compression chamber, a passage 100 communicating from said chamber to the combustion chamber, and a spring-pressed inlet check valve admitting fuel from the latter passage to said combustion chamber, whereby fuel is compressed during the 105 power stroke and during the exhaust such compression fuel forces its way through the inlet valve into the combustion chamber to expel the spent gases, and is further compressed therein during the return stroke.

3. An engine according to claim 1, the stationary piston fixedly mounted on an upright tubular support attached at its base to the end of the working cylinder, and the passage through said support forming part 115 of the passage leading from the compression chamber to the fuel inlet valve.

In witness whereof, we have hereunto signed our names in the presence of two subscribing witnesses.
